FURNACE CASING

Alan W. Duncan, Itasca, Ill., assignor to Sears, Roebuck and Co., Chicago, Ill., a corporation of New York

Application July 12, 1954, Serial No. 31,381

Term of patent 3½ years

(Cl. D81—2)

Fig. 1.

Fig. 2.

Fig. 3.

Fig. 1 is a front perspective view of a furnace casing embodying my new design;

Fig. 2 is a fragmentary elevational view of the front portion of a side of the same, and

Fig. 3 is a fragmentary plan view of the front portion of the top thereof.

Both sides of the casing are substantially the same, and the rear thereof is plain.

I claim:

The ornamental design for a furnace casing, as shown and described.
